UNITED STATES PATENT OFFICE.

JOSEPH F. MONTINE, OF NEVINVILLE, IOWA.

OVERHEAD MAIL OR PARCEL CARRIER.

1,122,785.

Specification of Letters Patent.

Patented Dec. 29, 1914.

Application filed March 18, 1914. Serial No. 824,551.

To all whom it may concern:

Be it known that I, JOSEPH F. MONTINE, a citizen of the United States, residing at Nevinville, in the county of Adams and State of Iowa, have invented new and useful Improvements in Overhead Mail or Parcel Carriers, of which the following is a specification.

The invention relates to electrically operated collection and delivery apparatus, and more particularly to the class of overhead mail or parcel carriers.

The primary object of the invention is the provision of an apparatus wherein mail, parcels or other articles to be collected and distributed along a route are placed within a receiver which is suspended from an elevated track, the receiver being electrically driven to have the same travel from point to point for the convenient handling of the matter throughout the route.

Another object of the invention is the provision of an apparatus wherein the hanger for the receiver is of novel form so as to absorb shocks and jars incident to the travel and also is connected to the receiver in a manner to afford the storing of articles therein.

A further object of the invention is the provision of an apparatus of this character wherein the speed of travel of the receiver is automatically controlled so that the speed can be diminished or increased at points in the route, as well as being stopped and started.

A still further object of the invention is the provision of an apparatus wherein the exchange of mail, parcels or the like to and from the carrier and station can be accomplished in a convenient manner for the collection and delivery thereof throughout a route.

A still further object of the invention is the provision of an apparatus of this character which is extremely simple in construction, thoroughly reliable and efficient in its operation, and inexpensive in installation.

With these and other objects in view, the invention consists in the construction, combination and arrangement of parts as will be hereinafter fully described, illustrated in the accompanying drawings, and pointed out in the claims hereunto appended.

In the drawings:—Figure 1 is a side elevation of an apparatus constructed in accordance with the invention. Fig. 2 is a

fragmentary vertical longitudinal sectional view thereof. Fig. 3 is a fragmentary vertical transverse sectional view. Fig. 4 is a horizontal sectional view through the motor 60 casing. Fig. 5 is an enlarged vertical sectional view through the speed controller for the motor. Fig. 6 is a fragmentary diagrammatic view showing the trip arm for the speed controller with relation thereto. 65 Fig. 7 is a vertical transverse sectional view through the track, showing the left hand curve therein. Fig. 8 is a similar view, showing the right hand curve in the track. Fig. 9 is a vertical sectional view through 70 the current rail.

Similar reference characters indicate corresponding parts throughout the several views in the drawings.

Referring to the drawings in detail, the 75 apparatus comprises a receiver A which may be of any desirable construction to receive mail, parcels or other articles to be transported from one point to another, and in one side of the receiver is a doorway B 80 to permit access to be had thereto, the receiver being suspended from and movable along an elevated track 10 fixed at predetermined intervals to supports 11 bolted or otherwise secured to a bracket 12 mounted 85 upon a pole 13 suitably anchored in the ground, it being understood of course that tracks can be arranged at opposite sides of the pole so that the receiver A can travel at either side if desired. 90

Arranged above the receiver A near each end thereof is a motor carriage C, which comprises a bed or base 14 on which are fixed twin motors 15 of the electric type, the rotary shafts 16 of which are fitted at 95 opposite ends with beveled gears 17 meshing with beveled pinions 18 fixed to opposite ends of stud shafts 19 arranged at right angles to the shaft 16 and supported in bearings 20, the said shafts 19 being fitted 100 with traction pulley wheels 21 arranged in pairs and working through slots 22 formed in the bed or base 14 to travel upon the track 10 for the driving of the receiver. On each bed or base 14 is fixed a casing or hood 105 23 forming a covering for each motor C.

Arranged parallel with the track 10 at the inner side thereof is an electric current wire 24, the same being supported at predetermined points by means of a bracket 110 25 which is fixed to the support 11 for the track 10, and adapted to travel on this wire

24 is a contact wheel 26, the same journaled at one end of an arm 27 pivoted to a stud 28 projecting laterally from the bed or base 14 of the motor C, and connected to the respective motors 15 and the stud 28 is wiring 29 so that the electric current from the wire 24 can be fed to the motors 15 for the driving thereof. Connected to the covering 23 and to an ear 30 on the arm 27 is a coiled tension spring 31 which serves to hold the wheel 26 in contact with the current wire 24 on the swinging of the receiver A during the travel thereof.

15 The peripheral treads 32 on the pulley wheels 21 are roughened to prevent the slipping thereof on the track while the receiver is in motion, the latter being suspended from each motor carriage C by means of a hanger D hereinafter fully described.

20 Each hanger D comprises a stem 33 which is suitably fixed in a boss 34 integral with and projecting beneath the bed or base 14 of the carriage C for connection therewith. The stem 33 is passed through a tubular column or sleeve 35 mounted in the receiver A and projected through the top or roof thereof, the said column or sleeve 35 being passed through a bearing 36 fixed to and at one side of an I beam 37 mounted internally of the receiver A, and also is passed through a collar 38 fixed to a cross sill 39 within the said receiver below the I beam 37. The sleeve 35 at its inner end has threaded thereon a nut 40 which works 35 against the collar 38, and in this manner the sleeve is mounted in the receiver. Surrounding the stem 33 between the bearing 34 and the sleeve 35 is a coiled compression spring 41 which serves as a shock absorber, 40 while splined or keyed to the inner end of the stem 33 are spaced disks 42, one of which has fixed therein guide pins 43, the same freely slidable through the other disk, and surrounding these pins 43 are coiled compression springs 44 which serve as shock absorbers.

50 The stem has fixed to its inner end a cup 45 which incloses the disks 42 with the pins and springs 44, it being apparent that the disks are longitudinally slidable on the stem 33, and threaded upon this stem is a nut 46 with which contacts one of the disks 42, and in this manner the said disks are held upon the stem. Each stem 33 is swiveled in 55 the receiver A so that the motor carriage C will readily take the curves 47 in the track 10.

50 Supported on the base or bed 14 of each carrier C at one side of the twin motors 15 is an electric speed controller 48 which is suitably wired to the said motors and has a rotatable star wheel 49 which is located at one side of the carriage C in the path of trip arms 50 and 51 respectively, which are 65 adapted to be arranged at intervals through-

out the length of the track 10, the arm 50 being designed to engage the wheel 49 at its lowermost point for causing the turning thereof in one direction, while the arm 51 is adapted to engage the said wheel at its uppermost point to rotate the same in the reverse direction, and in this manner the controller 48 is actuated for increasing or decreasing the speed of the twin motors 15 or for the starting or stopping thereof automatically. These arms 50 and 51 are each fixed in a suitable bracket 52 which is mounted upon the pole 13 to overhang the track 10 supported by the bracket 12 thereon. It is of course to be understood that when the motors 15 are to be started the wheel 49 has to be manually rotated for the turning on of the current from the wire 24 to the said motor, but by the tripping of the wheel 49 by a series of the arms 50 or 51 the said motors 15 can be gradually brought to a standstill for the stopping of the receiver at a predetermined point in the route, or at the terminals thereof. It is preferable to arrange the trip arms 50 or 51 at opposite sides of the curves 47 so that when the receiver A approaches the curve the speed of travel thereof will be gradually decreased, and after rounding the said curve 47 the speed of travel thereof will be increased by the automatic action of the controller 48 which is operated in a manner heretofore described.

It is to be understood of course that in lieu of the pairs of pulley wheels 21 and 100 their arrangement, any number of these wheels can be employed with the construction of suitable means to support the same on each carriage.

The apparatus can be constructed, that is, 105 the body of the carriage, for use in conveying passengers in lieu of mail or parcels, or it may be used for the conveying of any article, and this is contemplated within the invention.

110 From the foregoing it is thought that the construction and manner of operation of the device will be clearly understood, and therefore a more extended explanation has been omitted.

115 What is claimed is:—

1. An apparatus of the class described comprising an elevated track, an electric current carrying element disposed at one side of the track, motor carriages movable over the track and having electrically operated motors having movable connection with the current carrying element, a receiver arranged below the track, a boss depending from each carriage, tubular columns arranged within the receiver, stems fixed in and depending from the bosses and passed through the tubular columns, and shock absorbing devices arranged at the inner ends of the stems and working against 120 125 130

the said column for resiliently supporting the receiver.

2. An apparatus of the class described comprising an elevated track, an electric current carrying element disposed at one side of the track, motor carriages movable over the track and having electrically operated motors having movable connection with the current carrying element, a receiver arranged below the track, a boss depending from each carriage, tubular columns arranged within the receiver, stems fixed in and depending from the bosses and passed through the tubular columns, shock absorbing devices arranged at the inner ends of the stems and working against the said column for resiliently supporting the receiver, and resilient means disposed between the bosses and the said column and surrounding the stem.

3. An apparatus of the class described comprising an elevated track, an electric current carrying element disposed at one side of the track, motor carriages movable over the track and having electrically operated motors having movable connection with the current carrying element, a receiver arranged below the track, a boss depending from each carriage, tubular columns arranged within the receiver, stems fixed in and depending from the bosses and passed through the tubular columns, shock absorbing devices arranged at the inner ends of the stems and working against the said column for resiliently supporting the receiver.

ceiver, resilient means disposed between the bosses and the said column and surrounding the stem, and means for pivotally connecting the bosses to the said carriages to permit lateral swinging of the receiver.

4. An apparatus of the class described comprising an elevated track, an electric current carrying element disposed at one side of the track, motor carriages movable over the track and having electrically operated motors having movable connection with the current carrying element, a receiver arranged below the track, a boss depending from each carriage, tubular columns arranged within the receiver, stems fixed in and depending from the bosses and passed through the tubular columns, shock absorbing devices arranged at the inner ends of the stems and working against the said column for resiliently supporting the receiver, resilient means disposed between the bosses and the said column and surrounding the stem, means for pivotally connecting the bosses to the said carriages to permit lateral swinging of the receiver, and coöperative means arranged at intervals longitudinally of the track and on the motors respectively to serve as electric speed controllers for the latter.

In testimony whereof I affix my signature in presence of two witnesses.

JOSEPH F. MONTINE.
